UNITED STATES PATENT OFFICE.

HARRY P. MACDONALD, OF MONTCLAIR, NEW JERSEY, ASSIGNOR TO THE SNEAD & CO.
IRON WORKS, OF JERSEY CITY, NEW JERSEY, A CORPORATION OF NEW JERSEY.

PATTERN-DRAWING APPARATUS.

1,088,083.

Specification of Letters Patent.

Patented Feb. 24, 1914.

Application filed December 26, 1912. Serial No. 738,694.

To all whom it may concern:

Be it known that I, HARRY P. MACDONALD, a citizen of the United States, residing at Montclair, in the county of Essex and State 5 of New Jersey, have invented certain new and useful Improvements in Pattern-Drawing Apparatus, of which the following is a specification.

This invention relates to pattern drawing apparatus and it has for its primary objects; the provision in apparatus of the character described of improved operating mechanism; the provision of an improved arrangement of actuating and adjusting mechanism; the provision of improved means for maintaining an approximately constant load pressure on the operating mechanism; and the provision of an improved means for guiding the apparatus in 10 the drawing operations.

My invention further contemplates the driving of the apparatus by means of a motor and the provision of improved rapper mechanism actuated by said motor. A 15 further object resides in the provision of improved means for controlling the motor. These, together with such other objects as may hereinafter appear, or are incident to my invention, I obtain by means of a construction which I have illustrated in preferred form in the accompanying drawings, 20 wherein—

Figure 1 is a plan view of approximately half of the drawing apparatus with the pattern supporting table or plate broken away 25 to illustrate the operating mechanism; Figure 2 is an irregular, longitudinal section of the device taken on the line II—II of Figure 1; Figure 3 is a diagrammatic view 30 of the entire apparatus and indicates the operative positions of the actuating mechanism; Figure 4 is a sectional view, drawn on a larger scale, illustrating the rapper mechanism; Figure 5 is an end view of the rapper mechanism; Figure 6 is a section taken 35 on the line VI—VI of Figure 4; Figure 7 is a longitudinal section through the clutch mechanism, between the motor and the operating mechanism; Figure 8 illustrates the 40 electric wiring, the control switch and automatic cut-out switch; and Figure 9 is a section through one of the contact blocks of the cut-out switch, taken on the line IX of Figure 8.

One of the primary purposes for which

my invention is designed is the provision of a pattern drawing mechanism, adapted for use in drawing patterns of great length. Referring to Figures 1, 2 and 3 particularly, it will be seen that I have provided a main 60 frame 7 which contains the operating mechanism and the pattern supporting plate or table 8, the frame being closed at the bottom by means of the plate 9. The pattern table 8 closes the top of the frame, and the 65 ends of the frame are closed by means of plates 10.

The particular form of drawing apparatus illustrated is designed for use in connection with roll ramming apparatus, and 70 to this end I have provided a frame 7 with upstanding ledges 11 which serve to close the sides of the frame and also support the flask, which is filled with sand and rammed by a ramming roll in the usual manner.

From the foregoing it will be readily apparent that when the parts are assembled the frame provides a practically inclosed chamber in which the operating mechanism is contained. The advantage of this construction is that sand and other foreign matter which would be injurious to the operating mechanism is effectively excluded.

As previously stated, this device is particularly applicable for making molds for 80 long flat castings, and it is desirable to support the pattern table at a plurality of points on the operating mechanism. Briefly described, the operating mechanism comprises a vertical threaded shaft 12, such shaft being mounted in a saddle frame 13 in the central portion of the apparatus. Ball thrust bearings 14 are provided at the ends of the shaft. The shaft carries a block or nut 15, which in turn is connected to a pair of rock arms 16 and 17, keyed to the rock shafts 18 and 19, by means of the links 20 and 21, the rock shafts 18 and 19 being mounted in bearings in the saddle frame 13. Each rock shaft has keyed to it two rock 90 arms 22 and 22, said arms being connected to a pair of toggles 23 and 23 by means of the connecting rods or links 24 and 25. The toggles 23 and 23 are located substantially half way between the vertical operating shaft 12 and the ends of the frame 7. Located adjacent each end of the frame are a second set of toggle members 26 and 26, likewise arranged in pairs, said toggle members being connected to the links 24 and 25. 100 105 110

by means of links 27. The arrangement of toggle members and operative connections is clearly shown in Figure 3.

The upper lever of each of the toggle members is pivotally connected to the pattern table by means of the adjustable spindles 28 which project through bosses 29 formed on the bottom of the pattern support, and are secured by means of the nuts 30, the parts being so arranged that the nuts 30 are below, or at the most substantially flush with the upper surface of the pattern support. The lower lever of each toggle member is pivotally secured to the blocks 31 carried by the frame. It will thus be seen that I have provided an 8-point support for the pattern table, and that by turning the threaded spindles 28 the pattern support may be readily adjusted. The provision of the 8-point support and the arrangement of adjusting means is of peculiar advantage in apparatus of this kind in that it has been commonly found that patterns are not absolutely true, and it is frequently necessary to lower one corner or one edge of the pattern plate leaving the others at a different height. It will be readily seen that by my arrangement of operating mechanism any of the corners may be varied in elevation without necessarily disturbing the others, that is to say, any portion between the points of support may be warped with respect to the other portions, and herein lies one of the chief advantages of the 8-point support.

Adjacent the ends of the pattern support I have provided pairs of guide pins 32, said guide pins being adapted to engage apertured lugs 33 formed on the ends of the frame 7. In order to prevent sticking or binding of the guide posts, should it be necessary to vary the elevation of any one of the corners of the pattern support, I have mounted the guide posts in the pattern support in the following manner:

Recessed bosses 34 are cast on the under side of the pattern support and are adapted to receive the spherical ends 35 of the guide posts 32. The guide posts are placed in position and the pattern table is lowered and carefully leveled, the ends 35 of the guide posts lying within the recessed bosses 34 when the pattern table is in its lower or down position. The recesses are then filled with Babbitt metal 36, such metal serving to secure the guide posts in the pattern table or support while at the same time permitting of a slight movement of the guide posts when any of the corners of the pattern table are adjusted, the joint between being in effect a ball and socket joint. By this arrangement any of the corners of the table may be adjusted without causing the posts to bind in the frame 7, while at the same time the construction is such that the guide posts

prevent any longitudinal or lateral displacement of the pattern table.

In order to lock the pattern table and its operating mechanism in position for the ramming operation, and in order to relieve the operating mechanism of the load pressure of the ramming mechanism during the ramming operation, I arrange the toggles in such manner that they pass center and take against the abutments 37, adjustably mounted in the block 31. When the toggles have passed center they engage the abutments and the weight of the apparatus holds the parts in this position, and the drive shaft and the operative connections therefrom to the toggles, together with the motor for driving the shaft, are relieved from the load of the pattern table and of the ramming apparatus.

Another feature of the invention resides in the provision of means whereby the load pressure on the operating mechanism through the cycle of movement of the table is maintained at an approximately constant amount, thus securing evenness and continuity of the movement of the table and reducing the liability of injury to the molds. At the same time the motor and operative connections are relieved of undue stress. I accomplish this in the following manner.

The pattern support is provided with a plurality of downwardly projecting pins 38, which are in substantial alinement with the ends of the blocks 31 and with the brackets 31^a of the saddle blocks 13. The upper portions of the blocks and the brackets are recessed to receive compression springs 39, said springs being adapted to slip over the posts 38. These compression springs do not have sufficient strength to carry the load of the pattern table, but serve to cushion the table and assist the operating mechanism when the table is leaving or is returning to initial position, at which times the toggles act to least advantage.

I also provide a second set of springs 40, which are arranged in pairs at the ends of the pattern table. The springs 40 however, are tension springs and are secured at one end to the links 27 and at the other end to the frame 7 by means of the round headed screws 41. The spherical heads of the screws 41 permits the springs 40 to always stretch in a straight line. It will be apparent that when the table is in lower position the springs 40 exert their maximum tension on the toggles, and when the toggles are nearly vertical that the springs have contracted to approximately initial size, though they still have a large leverage on the toggles and exert considerable pull thereon because of the relation of the toggles to the table at that time.

This arrangement of springs is of special advantage, as it will appear that if the ver-

tical springs alone are used and such springs were strong enough to support considerable proportion of the weight of the pattern plate and pattern when the former is at its extreme upward position, then they would exert too much stress when the plate is lowered and the toggle mechanism is acting in a more disadvantageous position. Both the springs 39 and the springs 40 exert their greatest energy when the toggles are least effective in both the raising and the lowering movements of the table. By the use of vertical springs in connection with the horizontal springs acting directly on the toggles, the pattern plate is approximately in balance in all positions and a substantially constant load pressure is maintained on the operating mechanism at all periods of the movement of the table.

It will be readily understood that when the shaft 12 is rotated in one direction the nut 15 is drawn downward, and that when rotated in the other direction the nut 15 is elevated, and that these movements of the nut respectively secure the raising and the lowering of the pattern table. The shaft 12 is turned by the motor 42 by means of the following operative connections: A gear 43 is mounted on the upper portion of the shaft 12 and is engaged by the bevel gear 44 mounted on the end of the shaft 45, on the other end of which is mounted a worm wheel 46 which is turned by means of the worm 47 carried on the shaft 48, which is turned by the motor 42 through the clutch mechanism 49.

Referring to Figure 7 it will be seen that the clutch mechanism comprises two members 50 and 51, the member 50 being feathered to the shaft 52 of the motor 42, while the member 51 is keyed to the shaft 48. The member 50 rotates with the shaft 52 but has slight relative longitudinal movement with respect thereto. The end of the shaft 48 projects within the member 50 and is provided with a nut 53 and a spring 54, said spring being adapted to engage a bearing washer 55 carried in the member 50, and also to engage the nut 53. A friction disk 56 is located between the opposing faces of the members 50 and 51 and is held in position by reason of the fact that the spring 54 thrusts the member 50 toward the member 51. This arrangement of clutch mechanism causes the rotation of the shafts 48 and 45 when the motor 42 is running, but in case the motor should continue to run after the operating parts have reached their respective operative positions, the member 50 will slip on the friction disk 56 and prevent injury to the operating mechanism. The tension of the spring 54 can be varied by adjusting the nut 53.

Another advantage of my invention resides in the provision of a mechanical rap-

ping means operated directly from the motor which actuates the pattern drawing mechanism. I accomplish this by providing an arm 57 which has a bearing in the block 58 bolted to the side of the frame 7. One end 70 of the arm 57 projects within the frame 7, and the other end is connected by the arm 59 to the eccentric 60 mounted on the shaft 48. By this construction, when the motor is running, the eccentric 60 will cause the arm 57 75 to oscillate. The inner end of the arm 57 projects through a stirrup 61 which is bolted to the pattern table 8 and carries upper and lower anvils 62 and 63, which are preferably of hardened steel. The arm 57 is provided with a hammer 64, which is held in position by means of the shoes 65 and 66, these shoes being guided in the guideway of the stirrup 61. The hammer 64 can slide relative to the shoes inasmuch as the outer shoe is held in engagement with the hammer by means of the spring 67 carried in the end of the arm 57. While the hammer 64 will slide up and down as the arm 57 is oscillated by the eccentric 60, its movement will be retarded by the pressure of the spring 67 against the shoe 66. The hammer will rap the anvils smartly at each movement and thus secure the vibration of the pattern support and facilitate the drawing of the pattern. It will be apparent that the elevation of the pattern table will not affect the operation of the rapper.

This arrangement of rapper mechanism is very simple while at the same time it is positive in its action and does not stick or bind, as is frequently the case in pneumatic vibrator constructions. Another advantage of this construction resides in the fact that the weight of the blows delivered by the hammer 64 can be regulated by varying the tension of the spring 67 on the shoe 66. This is accomplished by adjusting the threaded block 68 in the end of the arm 57. Another advantage of the construction is that the need of a separate control mechanism for the vibrator is dispensed with inasmuch as the hammer 64 is actuated as soon as the motor is started.

The operation of the apparatus thus far described is as follows, assuming that the parts are in the position indicated in Figure 3, in full lines: The motor is actuated and turns the shaft 12 in such manner as to cause the nut 15 to move downwardly, such movement of the nut causing the rock shafts 18 and 19 to be rotated in the direction indicated by the arrows in Figure 2. This movement of the rock shafts imparts an outward movement to the rock arms 22, and 120 causes the sets of links 24, 25 and 27 to straighten out the eight toggle members, 125 thus elevating the pattern table.

The position of the parts when in upper position is illustrated in dotted lines in Fig. 130

ure 3. When in upper position the toggles have traveled slightly past center and take against the abutments 37, whereby the locking of the pattern table against downward movement is secured and the load pressure of the table taken off the operating shaft motor and operative connections. As soon as the parts have reached upper position the motor is stopped and the sand in the flask on the pattern table is rammed, after which the motor is actuated to turn the shaft 12 in the reverse direction, thus causing the nut 15 to rise and bringing the parts to initial position. This downward movement of the pattern table effects the drawing of the pattern. During both the upward and the downward movements of the pattern table the vibrator mechanism is being actuated by the motor and secures the effective drawing of the pattern. After the pattern is drawn the completed mold is removed in the usual manner. As previously pointed out, during the above described movements of the parts the springs 39 and 40 maintain an approximately constant load pressure on the operating mechanism.

It is desirable to have the motor automatically stopped at the limits of the movement of the operating mechanism, and to this end I have provided a control means consisting of a limit switch and a control switch. The limit switch comprises a switch plate 69 which is mounted on the shaft 18 and to which is pivotally mounted a pair of contact arms 70 and 71 which are normally held against the ends of the block 72 by means of the springs 73, one end of each of which is fastened to an arm and the other end to one of the pins 74. Secured to the framework of the apparatus is a fixed plate 75, preferably formed of non-conducting material, and which is provided with contact blocks 76 and 77, comprising a pair of plates which are spaced apart to provide grooves 78 into which the ends of the contact arms 70 and 71 fit.

The contact arms have a reasonably close fit in the grooves, so that when the switch plate 69 is rotated with the shaft 18, either one of the arms that happens to be in contact with a contact plate will lag slightly behind until it reaches the end of the contact plate, at which time a spring 73 will cause it to leave the groove with a snap so as to prevent electric arcing.

The springs 73 do not have sufficient strength to pull the contact arms 70 and 71 through the grooves, and I have provided set screws 94 and 95 threaded in brackets secured to the switch plate 69. When the switch plate is moving in the direction of the arrow the arm 71 will lag behind until the screw 94 abuts against it and carries it along with the switch plate. By adjusting the set screw the length of time that the arm is in

contact with the block 77 can be varied. The set screw 95 performs the same functions for the arm 70.

The control switch 82 is of the double pole double throw type, the pivot points 83 and 84 of which being connected to the main feed wires 85 and 86.

The parts being in the position indicated in Fig. 8, the motor is actuated to rotate the shaft 12 and raise the table by throwing the switch to engage the contacts A and B, and the circuit is completed, the current flowing from wire 85 through contact A and wire 88 to the right hand side of the armature, and thence through the wire 89, wire 90, contact arm 71, block 77, wire 91, contact B, and negative wire 86. As the table rises the rock shaft 18 is rotated in the direction of the arrow, until the arm 71 snaps out of the block 77 and thus breaks the circuit. This movement of the rock shaft brings the arm 70 into contact with the block 76. In order to lower the table, the switch is thrown into the position indicated in Fig. 8, and the current flows from main 85 through contact C, wire 92, block 76, arm 70, wire 93, wire 89, to the left hand side of the armature, and thence through wire 88, wire 94, contact D, and negative wire 86. The motor is reversed by changing the direction of the flow of the current through the armature, and rotates the shaft 12 in the reverse direction and lowers the table. The field windings are so connected that the direction of current therethrough is independent of the side to which the switch is thrown, so that the reversal of the switch merely changes the direction of the current through the armature. When the arm 70 snaps out of the block 76 the circuit is again broken.

It will be apparent that the control is simple, and that the entire operation of the device is conveniently accomplished. The limit switch and the motor and driving connections outside the main frame are inclosed in a casing or frame 7^a which permits of convenient access to the said parts, but effectively excludes sand or other foreign matter.

It will be apparent that the tension exerted on the toggle mechanism by the springs 40 may be varied by adjusting the screws 41.

Having thus described my invention and illustrated its use, what I claim as new and desire to secure by Letters Patent is the following:

1. In pattern drawing apparatus, the combination of a movable pattern supporting table, operating means for raising and lowering the table, and means whereby the load pressure of the table on the operating means is maintained approximately constant during the movement of the table.

2. In pattern drawing apparatus, the combination of a movable pattern supporting

table, toggle members for raising and lowering the pattern table, and means whereby the load pressure of the table on the toggle members during the cycle of movement of the latter is maintained approximately constant.

3. In pattern drawing apparatus, the combination of a movable pattern supporting table, toggle means for raising and lowering the pattern table, and means whereby the load pressure of the table on the toggle means during the cycle of movement of the latter is maintained approximately constant, said means comprising a counter-balance means exerting its maximum pressure on the toggle means when the latter is least effective, and exerting less pressure when the toggle means is most effective.

4. In pattern drawing apparatus, the combination of a movable pattern supporting table, toggle members for raising and lowering the pattern table, and means whereby the load pressure of the table on the toggle means during the cycle of movement of the latter is maintained approximately constant, said means comprising a counter-balance spring exerting its maximum pressure on the toggle means when the latter is least effective, and less pressure on the toggle means when the latter is most effective.

5. In pattern drawing apparatus, the combination of a movable pattern supporting table, toggles for raising and lowering the table, means for operating the toggles, and counter-balance springs connected to the toggles, exerting greatest pressure on the toggles when the toggles are least effective, and less pressure when the toggles are most effective.

6. In pattern drawing apparatus, the combination of a frame, a movable pattern table therefor, a toggle for raising and lowering the table, means for operating the toggle, and a tension spring one end of which is secured to the frame at one end and at the other to the toggle, said spring exerting its greatest tension when the toggle acts to least advantage.

7. In pattern drawing apparatus a frame, a movable pattern table therefor, a plurality of toggles for raising and lowering the table, a common means for operating the toggles, and counter-balance means for maintaining the load pressure of the table on the operating mechanism approximately constant during the movement of the table, said means comprising tension springs secured at one end to the toggles and at the other to the frame, and exerting a maximum tension when the toggles act to least advantage.

8. In pattern drawing apparatus a frame, a movable pattern table therefor, a plurality of toggles for raising and lowering the table, means for operating the toggles,

and counter-balance means for maintaining the load pressure of the table on the operating mechanism approximately constant during the movement of the table, said means comprising compression springs secured at one end to the toggles and at the other to the frame, said springs exerting maximum pressure when the toggles act to least advantage, and less pressure when the toggles act to best advantage.

9. In molding apparatus the combination of a movable pattern supporting member or table, a multi-point support for said table, connections between the support and the table whereby any portion of the table may be varied in elevation with respect to other portions, and guide means for the table adapted to prevent lateral displacement of the table but permitting of vertical adjustment of portions of the table with respect to other portions without binding.

10. In molding apparatus, the combination of a movable pattern supporting member or table, a multi-point support for said table, connections between the support and the table whereby a portion of the table can be varied in elevation with respect to other portions thereof, and swiveled guide means preventing lateral displacement of the table but permitting adjustment of portions of the table without binding.

11. In molding apparatus the combination of a frame, a movable pattern supporting table therefor, a multi-point support for said table, connections between the support and the table whereby any portion of the table can be varied in elevation with respect to other portions thereof, and a guide post having a ball and socket connection with the table engaging the frame and preventing lateral displacement of the table.

12. In molding apparatus, the combination of a movable pattern supporting member or table, a motor for raising and lowering the table, and a reciprocative rapper mechanism for vibrating the table as it is moved by the motor and an operative connection between the motor and the rapper mechanism.

13. In molding apparatus, the combination of a movable pattern table or support, a rapper carried thereby and having reciprocative movement, a relatively fixed motor, and an operative connection between the motor and the rapper whereby the rapper is actuated to vibrate the table, said operative connection having a sliding engagement with the rapper.

14. In molding apparatus, the combination of a movable pattern table or support, a rapper carried thereby and having reciprocative movement, a relatively fixed motor, and an operative connection between the motor and the rapper whereby the rapper is actuated to vibrate the table, said opera-

tive connection having sliding frictional engagement with the rapper.

15. In molding apparatus, the combination of a movable pattern table or support, 5 a reciprocating rapper carried thereby, a relatively fixed mechanical means for imparting vertical reciprocative movement to the rapper, and a slip connection between the actuating means and the rapper whereby the 10 rapper is actuated but is free to move with the table.

16. In molding apparatus, the combination of a support, a movable pattern table, a motor carried on the support, a reciprocating 15 rapper carried by the movable table, an oscillating arm mounted on the support operated from the motor, and a sliding connection between the arm and rapper.

17. In molding apparatus, the combination 20 of a support, a movable pattern table, a motor carried on the support, a rapper carried on the table, an oscillating arm pivoted to the support, an eccentric operated by the motor for oscillating the arm, and a slip connection between the rapper and the arm.

18. In molding apparatus, the combination 30 of a support, a movable pattern table, a motor carried on the support, a stirrup on the table, a rapper bar therefor, an oscillating arm pivoted to the support; an eccentric operated by the motor for actuating the arm, and a friction connection between the arm and rapper bar.

19. In molding apparatus, the combination 35 of a support, a movable pattern table, a motor carried on the support, a stirrup on the table, a shoe slideable in the stirrup, a rapper bar slideable in the shoe, an oscillating arm pivoted to the support, and an eccentric 40 operated by the motor for actuating the arm, said arm engaging the shoe.

20. In molding apparatus, the combination 45 of a support, a movable pattern table, a motor carried in the support, a stirrup carried by the table, a pair of shoes slideable in the stirrup, a rapper bar slidably mounted between the shoes, an oscillating arm pivoted to the support and engaging the shoes, yielding means for holding the shoes in engagement with the rapper bar, an eccentric 50 operated by the motor for actuating the arm.

21. In molding apparatus the combination 55 of a support, a movable pattern table, a motor carried in the support, a stirrup carried by the table, a pair of shoes slideable in the stirrup, a rapper bar slidably mounted between the shoes, an oscillating arm pivoted to the support and engaging the shoes, spring means for holding the shoes in engagement with the rapper bar, means for 60 adjusting the tension of the spring means, and an eccentric operated by the motor for actuating the arm.

22. In a molding apparatus, the combination 65 of a support, a movable pattern table,

a motor carried on the support, a rapper, an oscillating arm mounted on the support operated from the motor and a connection between the arm and the rapper.

23. In molding apparatus, the combination 70 of a movable pattern table or support, a reciprocating rapper, a relatively fixed motor, and an operative connection between the motor and the rapper whereby the rapper is actuated to vibrate the table, said operative connection having a sliding engagement with the rapper.

24. In molding apparatus the combination 75 of a frame, a movable pattern table mounted therein, guideways in the frame, 80 guide posts engaging the guideways having a ball and socket connection with the table, and means for varying the angular inclination of the table.

25. In molding apparatus the combination 85 of a frame, a movable pattern table mounted therein, guideways in the frame, guide posts engaging the guideways having a ball and socket connection with the table, and means whereby a portion of the table may be 90 flexed relative to other portions thereof.

26. In molding apparatus the combination 95 of a movable pattern table, means for raising and lowering the table, a reciprocating rapper for vibrating the table as it is moved, and a relatively fixed mechanical operating member for the rapper, the rapper being 100 slidably mounted on said member so as to accommodate itself to variations in the vertical position of the table.

27. In molding apparatus the combination 105 of a pattern table or support, adapted to be raised and lowered, a rapper for vibrating the table as it is being moved, and a relatively fixed operating member for the rapper, said rapper having slidable engagement with the operating member.

28. In molding apparatus the combination 110 of a movable pattern supporting table, means for raising and lowering the table, the table being supported on said means at a plurality of points, means whereby a portion of the table between points of support can be warped, and guide means for guiding the table in its raising and lowering movements, 115 said guide means having a mounting whereby the table can be warped without causing binding of the guide means.

29. In molding apparatus the combination 120 of a movable pattern supporting table, means for raising and lowering the table, the table being supported on said means at a plurality of points, means whereby a portion of the table between points of support can be warped, and guide posts for guiding the 125 table in its raising and lowering movements, said guide posts having a mounting whereby the table can be warped without causing binding of the guide means.

30. In molding apparatus, the combination 130

of a movable pattern table or support, a rapper bar for vibrating the table, having vertical reciprocative movement and movable with the table, a relatively fixed mechanical means for reciprocating the rapper, and an operative connection between said means and the rapper, the said rapper having a frictional sliding engagement with said connection whereby the rapper is free

to move with the table while being reciprocated.

In testimony whereof I have hereunto signed by name in the presence of the two subscribed witnesses.

HARRY P. MACDONALD.
